WALTER N. STEVENSON, OF EVANSTON, ILLINOIS, ASSIGNOR TO F. J. LITTELL
MACHINE CO., OF CHICAGO, ILLINOIS, A CORPORATION OF ILLINOIS.

FEEDING MECHANISM FOR WORK PIECES.

1,424,785.

Specification of Letters Patent. Patented Aug. 8, 1922.

Application filed January 3, 1921. Serial No. 434,770.

To all whom it may concern:

Be it known that I, WALTER N. STEVENSON, a citizen of the United States, residing at Evanston, in the county of Cook and 5 State of Illinois, have invented certain new and useful Improvements in Feeding Mechanism for Work Pieces, of which the following is a specification.

This invention relates to means for feeding blanks or work-pieces into position to 10 be acted upon by a machine, such, for instance, as a press, punch, or the like. It has for its primary object to provide means which will receive the work-piece either 15 from an automatic feed or from the hands of a workman at a point of safety, and automatically deliver the same to a machine which is to operate upon it; the invention being particularly designed to insure accurate 20 delivery of the work-piece and depress it from the path of introduction to a position in which it is to be operated on so that it may be seated in a hollow die or over a protruding die or post, as the nature of the 25 work may require. The invention has for a further object the provision of simple and effective means through which to realize the above-mentioned primary object.

The invention proceeds upon the principle 30 of having a sliding carriage for introducing the work-piece into the path of the machine which is to act upon it, preferably controlled by the working stroke of the tool of such machine so that the introduction of 35 the work-piece is timed with relation to the working stroke, and a displacing means mounted on the introducing carriage whereby the work-piece is moved out of the path of introduction and into a seat upon the bed, 40 die, or other support with which the tool cooperates. In the preferred embodiment of the device the reciprocating portion of the machine acts through a cam upon the introducing carriage to develop the return 45 stroke of the latter, while a spring or springs connected with the carriage and its frame constantly tend to move the carriage in the direction to present the work-piece; and the displacing means comprises a pivotally 50 mounted presser foot having a spring for normally moving it in a direction to displace the work-piece from the path of introduction, and a cam for withdrawing it which

acts upon the displacing means during the return stroke of the latter. 55

In the accompanying drawings:

Figure 1 is a side elevation of the plunger and bed of a die press with which one embodiment of the subject-matter of the present invention is incorporated by way of illustration; and 60

Figure 2 is a front elevation of parts shown in Figure 1, minus the plunger.

A represents the bed and B the plunger of a die press, of which the former has a 65 hollow seat A' to receive the work-piece, and the latter carries the punch B' for acting upon the work-piece. Obviously, the devices A' and B' are merely illustrative of numerous forms of punching, pressing, shaping, riveting, or other tools that might be employed between the relatively movable members of a press. It will be noted, however, that the seat A' is out of the plane of 70 the path through which the work-piece is introduced to the press. For the purpose of introducing the work-piece, a slide C is mounted in guide member D provided with a spring E anchored to the slide at E' and to the guide at E², and acting to constantly 75 press the slide C toward the press. Slide C is further provided with a camming member F, preferably in the form of a horn projecting from the slide and constructed with a slot F' receiving one arm G' of the lever G 80 which is fulcrumed at H' on the bracket H, and has its other arm G² presented in the path of a projection I on the plunger B, so that each time the plunger descends and 85 the arm G² is displaced, the arm G' is moved to the rearward and the slide C is withdrawn from introducing position; whereas upon withdrawal of the plunger B, the lever G is permitted to swing in the opposite direction under the influence of the slide C 90 driven by spring E and a new work-piece is introduced. 95

Mounted on the slide C is the displacing member K comprising a lever fulcrumed at K' with a spring K² swinging it upon said 100 fulcrum in the direction to throw its forward end downward, and having a finger K³ adapted to engage a stop K⁴ to limit its downward movement. Lever K is further provided with a friction roller K⁵, that plays over 105 the cam L, and upon its forward end it car-

ries a resilient presser foot K⁶ that is adapted to overlie a work-piece, such, for instance, as shown at X, so that when the slide C moves forward and the roller K⁵ runs down the inclined forward end of the cam L, the presser-foot K⁶ will displace the work-piece X from the path of introduction and seat it in position to receive the plunger. This displacement from the path of introduction 10 may be a complete seating of the work-piece, as, for instance, starting it in the right direction and permitting the seating action to finish by gravity, or it may be a complete positive displacement of the work-piece to 15 its seat, or it may simply displace the work-piece a part of the distance toward its seat so that the plunger will force it completely to its seat in acting upon it. The slide C will preferably carry adjacent the work-piece X a pusher M to engage the work-piece in the direction of introduction to the press, and this pusher may have any approved form adapting it to properly control the work-piece in the plane of introduction.

20 25 I claim:

1. A feeding means for presses comprising an introducing member adapted to travel in a path to introduce a work-piece to the press, and a displacing member mounted 30 upon and partaking of the introducing movements of the introducing member, and having an independent movement thereon to move the work-piece from the path of introduction when it arrives in position to receive the action of the press.

2. A feeding means for presses comprising an introducing member adapted to travel in a path to introduce a work-piece to the press, and a displacing member mounted 40 upon and partaking of the introducing movements of the introducing member and having an independent movement thereon to move the work-piece from the path of introduction when it arrives in position to receive the action of the press; said displac-

ing member receiving its displacing movements from the movement of the introducing member.

3. A feeding means for presses comprising a sliding carriage adapted to introduce a work-piece to the press, a displacing member pivotally mounted on said carriage in position to overlie a workpiece being fed by the carriage, and means for imparting movement to said displacing member transversely to the path of introduction.

4. A feeding means for presses comprising a sliding carriage adapted to introduce a work-piece to the press, a displacing member pivotally mounted on said carriage in position to overlie a work-piece being fed by the carriage, and means for imparting movement to said displacing member comprising a spring for swinging said member in one direction and a cam for moving it in 60 the other direction.

5. A feeding means for presses comprising a sliding carriage adapted to introduce a work-piece to the press, a displacing member pivotally mounted on said carriage in position to overlie a work-piece being fed by the carriage, and means for imparting movement to said displacing member transversely to the path of introduction; said displacing member having a resilient presser foot 70 through which it acts upon the work-piece.

6. Means for feeding work-pieces to a press comprising a carriage adapted to receive a work-piece and present it to the press, a displacing member movably mounted on said carriage, means moving said displacing member on said carriage, transversely to the path of the carriage before the work-piece reaches the press, and a resilient presser foot 80 through which the displacing member acts 85 upon the work-piece.

Signed at Chicago, Illinois, this 30th day of December, 1920.

WALTER N. STEVENSON.
